UNITED STATES PATENT OFFICE.

SHERWOOD HINDS, OF GALESBURG, MICHIGAN.

DESIGN FOR A VENDING-MACHINE CASING.

Application filed October 16, 1925. Serial No. 15,146. Term of patent 3½ years.

To all whom it may concern:

Be it known that I, SHERWOOD HINDS, a citizen of the United States, and a resident of Galesburg, Kalamazoo County, Michigan, have invented a new, original, and ornamental Design for a Vending-Machine Casing, of which the following is a specification, reference being had to the accompanying drawing, forming part hereof, in which—

Fig. 1 is a front elevation of the article, showing my new design; and Fig. 2 is a side elevation.

I claim:

The ornamental design for a vending machine casing substantially as shown.

In testimony whereof, I have signed my name to this specification this 26th day of September, 1925.

SHERWOOD HINDS.
